(57) **CLAIM**

(21) Appl. No.: **29/345,673**

The ornamental design for a light irradiation device for print machine, as shown and described.

(22) Filed: **Oct. 20, 2009**

DESCRIPTION

(30) **Foreign Application Priority Data**

Apr. 20, 2009 (JP) 2009-009018

FIG. 1 is a front view of a light irradiation device for print machine;

(51) **LOC (9) Cl.** **18-02**

FIG. 2 is a right side view thereof;

(52) **U.S. Cl.** **D18/56**

FIG. 3 is a top plan view thereof;

(58) **Field of Classification Search** D18/56; D23/213; 239/223, 225.1, 290, 291, 292; 427/475; 118/300

FIG. 4 is a rear view thereof;

See application file for complete search history.

FIG. 5 is a bottom plan view thereof;

(56) **References Cited**

FIG. 6 is a left side view thereof;

U.S. PATENT DOCUMENTS

FIG. 7 is an enlarged right side view thereof;

FIG. 8 is an enlarged left side view thereof;

FIG. 9 is an enlarged 9-9 partial view thereof, of FIG. 1;

FIG. 10 is a 10-10 cross-sectional view showing an outline thereof without internal structure of FIG. 1;

FIG. 11 is an enlarged 11-11 cross-sectional view showing an outline thereof without internal structure of FIG. 5;

FIG. 12 is an enlarged partial view between 12-12 and 12-12 of FIG. 9 thereof;

FIG. 13 is a reference plan view thereof in use;

FIG. 14 is a reference plan view thereof in use; and,

FIG. 15 is an enlarged reference 11-11 cross-sectional view thereof in use.

The broken lines and hatchings shown in drawings are for illustrative purposes only and form no part of the claimed design. The long dash short dash line forms the boundary of the claimed design and forms no part of the claimed design. The double-hatchings shown in FIGS. 11 and 15 indicate that the part is made of transparent materials.
